VELOCIPEDE NOISEMAKING ATTACHMENT

Carol M. Eberhardt, 1697 York Ave.,
St. Paul, Minn. 55106

Filed Jan. 23, 1969, Ser. No. 15,474

Term of patent 14 years

Int. Cl. D12—14

U.S. Cl. D90—1

Fig. 1

Fig. 2

Fig. 3

Fig. 4

FIGURE 1 is a perspective view of a velocipede noisemaking attachment showing my new design;

FIGURE 2 is a side view of the velocipede noisemaking attachment shown in FIGURE 1;

FIGURE 3 is a bottom view of the velocipede noisemaking attachment of FIGURES 1 and 2; and

FIGURE 4 is a side view of the other side of the velocipede noisemaking attachment shown in FIGURE 2.

I claim:

The ornamental design for a velocipede noisemaking attachment, substantially as shown.
